US0D1058183S

(12) United States Design Patent (10) Patent No.: US D1,058,183 S
(45) Date of Patent: * Jan. 21, 2025

(54) MIRROR

(71) Applicant: Dongguan Powerme Tech. Co., Ltd,
Dongguan (CN)

(72) Inventor: Guowei Yang, Dongguan (CN)

() Term: 15 Years

(21) Appl. No.: 29/942,763

(22) Filed: May 17, 2024

(51) LOC (15) Cl. 06-07

(52) U.S. Cl.
USPC D6/300; D6/308

(58) Field of Classification Search
USPC D6/300, 308-310, 312; D14/341;
D28/64.2, 64.3
CPC A45D 42/00; A45D 42/10; A45D 42/16
